UNITED STATES PATENT OFFICE.

THOMAS F. HALL, OF SAN JOSE, CALIFORNIA, ASSIGNOR OF ONE-FOURTH TO GEORGE C. ANDERSON AND ONE-FOURTH TO WILLIAM H. ANDERSON, BOTH OF SAN JOSE, CALIFORNIA.

PORTIÈRE.

1,001,756.

Specification of Letters Patent. Patented Aug. 29, 1911.

Application filed September 17, 1910. Serial No. 582,492.

To all whom it may concern:

Be it known that I, THOMAS F. HALL, a citizen of the United States, residing at San Jose, in the county of Santa Clara and State 5 of California, have invented new and useful Improvements in Portières, of which the following is a specification.

The present invention relates to improvements in open work portières, such as are 10 commonly made of leather or similar flexible material, the object of the invention being to provide an improved construction of such portières, by which they can be manufactured at a comparatively low cost and 15 will yet present a pleasing and attractive appearance.

In the accompanying drawing, Figure 1 is a front view of a portière constructed 20 in accordance with my invention; Fig. 2 is a similar enlarged view of a portion thereof; Fig. 3 is a plan view of one of the links thereof extended; Fig. 4 is a similar view of another link.

Referring to the drawing, 1 indicates a 25 rod upon which the portière is suspended. Said portière is constructed principally of segments or links 2, 3, which are of two forms. Each link of either form consists of a strip of leather or similar material having 30 a contracted middle portion 4, its two halves being symmetrical. At each end it is formed with an aperture, which in the form of a link shown in Fig. 3, is circular, as shown at 5, the terminal portions 6 of said link 35 being also circular, and the edges thereof being at a constant distance from the apertures. In the form of link shown in Fig. 4, the terminal apertures 7 are triangular. Between the middle and each end, each link 40 of either figure is formed with a diamond-shaped aperture 8, and, in that shown in Fig. 3, the edges of the link are, between the middle and terminal portions, parallel with the sides of said apertures 8. In the 45 form shown in Fig. 4, these edges between the middle and the ends are straight and parallel with each other.

The links are connected together by passing one link through the two terminal aper-

tures of an adjacent folded link, and then 50 folding it together about the middle, so that its middle portion engages said terminal apertures. The links are thus connected to form chains or bands.

The links shown in Fig. 4 are particularly 55 adapted to form hangers, to each of which, at the end 9, may be attached a single link of the form shown in Fig. 3, to the lower portion of which link may be also attached a tassel 10. The links of the form shown in 60 Fig. 3 are particularly well adapted for connections in lines extending crosswise of each other. For this purpose the ends of two links are placed overlapping or in register with each other, so that the circular 65 apertures in said ends register, and two other links are then inserted through said apertures and folded therein about their middle portions. It is for this reason that the ends of the links surrounding said circular 70 apertures are made with edges circular and at a uniform distance from the apertures, so that, when they are connected at different angles, and the other links are attached thereto, all of said links will appear 75 to radiate from a common circle, and the connected links will present a uniform and regular appearance.

I claim:—

A device of the class described, comprising 80 links, each formed with a contracted middle portion and with apertured ends, two of said links having their terminal apertures registering with each other, and the links extending from said apertures ap- 85 proximately at right angles, and two other links having their middle portions passing through said four apertures and extending substantially in line with the first-named links, substantially as described. 90

In testimony whereof I have hereunto set my hand in the presence of two subscribing witnesses.

THOMAS F. HALL.
